AUTOMATIC STOP DEVICE

William C. R. Jones, Beauharnois, Quebec, Canada, assignor to Howard Smith Paper Mills Limited, Montreal, Quebec, Canada

Application March 3, 1947, Serial No. 732,036

2 Claims. (Cl. 270—39)

1

This invention relates to automatic stop devices for machines for folding and interleaving sheets of paper such, for example, as cigarette paper intended for individual rolling of cigarettes.

More specifically, the invention relates to automatic stop devices for folding and interleaving machines equipped with the interleaving apparatus of the so-called intermeshing "star wheel" type.

The conventional "star wheel" interleaving apparatus of machines to which this invention relates comprises two wheel members, each presenting a circular series of triangular teeth separated by intervening V-shaped notches. The two wheel members are continuously rotated in opposite directions about parallel horizontal shafts which are spaced apart so that the teeth of one wheel member meshes with the teeth of the companion wheel member while travelling in a downward direction. A loading station is located above each wheel member. At this station mechanism is provided for feeding a continuous strip of cigarette paper from a supply reel, cutting the strips transversely to provide individual cigarette papers of conventional length and width and folding each individual cigarette paper along a fold line located centrally of its width. After being folded, each individual paper is dropped into a passing notch of the underlying wheel member and opens up so that the folds or sides of the paper lie substantially flat against the sloping side walls of the notch. This results in the sides of the paper described in each notch of one wheel being interleaved in the conventional zig-zag interleaving fashion with the sides of two papers deposited in two adjacent notches of the companion wheel as the teeth of the two wheels are brought into interfitting or meshing relation. In order to prevent accidental displacement of the papers deposited therein, the cigarette paper carrying notches of the two wheels are connected with a source of suction from the time they reach the loading station until they arrive at the point where the interleaving occurs.

The interleaving apparatus referred to above is provided with means whereby cardboard divider strips are included in the stream of continuously interleaved cigarette papers to facilitate the subsequent division of the stream into separate and equal packets for packaging purposes.

With the foregoing in mind it will be seen that paper is fed from the two supply reels to a pair of cutters under normal conditions as a continuous strip to each cutter. The cut paper is then folded and fed without interruption to the notches of the star wheels as they pass under their loading stations and are held to the side walls of the notches by suction prior to the inter-

2

leaving process. It is, therefore, essential that a folded paper be fed to every successive notch in the star wheel mechanism in order to provide each packet with its full complement of cigarette papers. However, for various reasons, such as weakness in the paper or undue stress from the feeder mechanism, the paper being fed from the supply reel to the cutter is subject to breakage. This causes a discontinuance of the flow to at least one of the cutters. Unless this breakage is immediately spotted, considerable waste is encountered in the continuance of the machine since the supply will continue to the second cutter and the subsequent feed will only be to one of the interleaving star wheels. Likewise, the continuous feed to the notches of the star wheels is apt to be interrupted, due to a jamming in the folding and feeder mechanism of the loading station or other mechanical defects, so that one or more of the notches are skipped. This not only causes unequal distribution of cigarette papers to the packet but also disrupts the interleaving of the papers with the result that subsequent packets are also improperly interleaved. Unless the machine is immediately stopped, a sustained jamming in the one loading station might result while the other continued to supply the folded cigarette papers and dividers to the star wheel mechanism causing so much additional waste in paper. On the other hand, the jamming might correct itself after one or two skips and go by unnoticed by the operator, resulting in an unequal supply of papers to a packet as well as faulty interleaving of the papers. When such a packet is spotted by an inspector it is sometimes necessary to discard large batches of cigarette papers to ensure that faulty packets are not released for sale.

It is the object of this invention to provide automatic means for stopping the cigarette paper folding and interleaving machine whenever the feeding of paper is interrupted.

A further object of this invention is to provide a device which will register a break in the flow of paper from the reel to the cutter mechanism and thereby automatically discontinue the operation of the folding and interleaving machine.

A still further object is to provide means for registering the interruption of the successive feeding of folded papers to the star wheel mechanism and for automatically stopping the machine when such an interruption occurs.

Another object of this invention is to provide an operating means, actuated by an interruption detector device for stopping the cigarette paper folding and interleaving machine whenever interruption of the continuous supply of cigarette paper takes place.

These and other objects, advantages and characteristic features of the invention will be more

readily understood from the following detailed description taken in connection with the accompanying drawings, in which—

Fig. 1 is a front elevational view of a cigarette paper folding and interleaving machine of the "star wheel" type, showing the automatic stop devices embodied in my invention.

Fig. 2 is a side elevational view of the machine shown in Fig. 1.

Fig. 3 is a section taken along the line 3—3 of Fig. 2, showing the operation of the solenoid actuated clutch disengaging mechanism.

Fig. 4 is a wiring diagram of a relay mechanism employed in operation of my automatic stop devices.

With reference to the drawings, the general arrangement of a folding machine consists of a main stand 10 mounted on a base 11. The stand 10 supports a pair of bobbins of cigarette paper indicated at 12. The paper from each bobbin unwinds over a guide roller 13 and between a creasing mechanism 14 comprising upper and lower plates 14a and 14b which impart a permanent crease to the paper in the middle as it goes by. The paper then passes between a pair of feed rolls 15 and from there is directed to a cut-off table 16 where the paper is cut into desired lengths for individual cigarette papers by a cutter 17. Each individual paper is then folded along its crease line by means of a blade 18 which is given a downward stroke by the operating mechanism of the machine. The downward stroke of blade 18 pushes the folded cigarette paper through a slot in a box-like loading station 19 located over a "star wheel" 20. A folded paper in each loading station then drops into each individual groove 21 defined between the teeth 22 of a pair of star wheels 20 which are mounted to rotate in opposite directions and in meshing engagement with one another. The papers are held in place in the groove of the star wheel by suction until they are interleaved in the well known manner of the conventional "star wheel" type machines. The interleaved papers are then fed downwardly through a magazine 23 onto a conveyor 24, in the conventional manner of such machines, as finished folded paper ready for the packaging machines.

As above stated, considerable wastage of the paper has been encountered due to disruption in the continuous flow of paper from one or the other of the bobbins to the star wheels. I have therefore provided, at strategic points between the bobbins 12 and the star wheels 20, electrical contact means which closes the electrical circuit, at the point where flow of paper has been interrupted, to thereby actuate a device for stopping the machine immediately there is a break or stoppage of the paper in the machine.

An electrical contact means comprising an L-shaped bracket 25 is mounted on each side of stand 10 between the cigarette paper guide roller 13 and creasing mechanism 14. Bracket 25 is pivotally suspended from a post 26 projecting from stand 10 so that the lower marginal portion of depending arm 27 of bracket 25 will normally ride on the upper surface of the cigarette paper as it is fed from bobbin 12 to cut-off table 16 by means of feed rolls 15. When the lower arm 27 is riding on the paper, the upper arm 28 is projected over but out of contact with upper plate 14a of creasing mechanism 14. Post 26 is insulated from the stand 10 and bracket 25 is electrically connected to any suitable circuit arrangement such as a relay mechanism 29 mounted on

the base 11, by means of an electrical conductor wire indicated in the wiring diagram (Fig. 4) of the appended drawings. The relay 29 is grounded on the stand 10 (see wiring diagram) and the operation of said relay will be more fully dealt with in a subsequent part of the specification. When there is a break in the paper between the bobbin 12 and feed rolls 15, as indicated by dotted lines in Fig. 4, the upper arm 28 of bracket 25 is permitted to swing downwardly about its pivotal connection to contact the grounded stand 10 through said upper plate 14a. This closes the electrical circuit which induces relay 29 to actuate a solenoid mechanism, as indicated at 30, which serves to disengage a clutch mechanism and thereby stop the machine.

A further electrical contact means is mounted over each of the star wheels 20. This contact means consists of a bar 31 of fine shim steel, or other suitable metallic substance. One end of the bar is pivotally mounted on an insulated post 32 to suspend said bar over the teeth of said star wheel at a suitable point intermediate the loading station and the point where interleaving of the cigarette papers occurs. Bar 31 is electrically connected to relay 29 by means of an electrical conductor wire indicated in the wiring diagram. The bar is bent intermediate its length with its free end projecting in the direction of rotation of star wheel 20 so that it will ride freely over the points of the star wheel. The cigarette papers deposited in the grooves of the star wheel have their side edges projecting slightly beyond the points of said star wheel and thereby serve to keep bar 31 from, making contact with said star wheel under normal operating conditions. However, should a break or stoppage in the distribution of cigarette papers to the star wheel grooves occur, bar 31 will drop into the first empty groove and establish contact with the star wheel 20 which is grounded to relay 29 through stand 10. This contact with star wheel 20 closes the electrical circuit to relay 29 which actuates solenoid 30 to disengage the aforesaid clutch mechanism.

The folding and interleaving machine is driven by an electric motor 35 which is connected by a series of pulleys and belts, generally indicated at 36, to rotate a shaft 37 which is engageable with a driving shaft 38 by means of a clutch mechanism 39. The clutch mechanism is actuated by a lever 40 having one end pivotally secured thereto by pivotal means 41. The lever is fulcrumed at an intermediate point about a pin 42 to a bracket 43 extending from the rear of stand 10. The lower end 44 of lever 40 is connected to one end of a clutch lever actuating rod 45 which is positioned at one side of stand 10 with its free end projecting beyond the front face of said stand. The rod is movable forward and rearwardly, said movement being manually controlled by a crank member 46 mounted on the free end of said rod which, when the rod is rotated, causes a key 47, secured to rod 45, to ride on an inclined surface of a cam member 48 in which said rod is slidable. The rearward movement of rod 45 pushes the lower end 44 of lever 40 rearwardly. The lever, pivoting at its fulcrum point about pin 42, moves the clutch 39 into engagement with machine driving shaft 38, as shown in full line. When rod 45 is moved to its forward position, lever 40 slides clutch 39 rearwardly out of engagement with drive shaft 38, as indicated in dotted line, to stop the machine. An automatic means which is actuated by relay 29 has been provided for disengaging clutch

mechanism 39. Said means comprises a solenoid 30 secured to one side of stand 10 and a lever arm 50 carried by rod 45 and adapted to be tripped by the trip bar 51 of solenoid 30. Lever arm 50 serves to rotate rod 45 to throw the clutch 39 out of engagement with machine driving shaft 38. Normally lever arm 50 projects horizontally from rod 45 when the machine is operating and trip bar 51 of the deenergized solenoid is in its lowered position beneath the free end of said lever arm. If a break or stoppage in the distribution of the cigarette paper occurs, electrical contact means 25 or 31, by closing the circuit, induces relay 29 to actuate the solenoid 30. The energized solenoid raises trip bar 51 which trips lever arm 50 to rotate rod 45. A toggle 52 straddling rod 45 has one end pivotally connected to an intermediate point on lever arm 50 and the other end fastened to a tension spring 53 which is secured to stand 10 as indicated at 54. The toggle is arranged so that when lever arm 50 is disposed horizontally to rod 45 the spring tension on the toggle and the toggle tension on the lever arm are centered with the axis of rotation of the lever arm preventing movement of the lever arm by the spring and toggle mechanism. When lever arm 50 is tripped by solenoid tripping bar 51, the said centering is disrupted and the tension of the spring and toggle mechanism serves to complete rotation of rod 45 to thereby disengage the clutch 39 for stopping the machine.

A signal or warning lamp 55 mounted on the stand 10 is lighted at the same time that solenoid 30 is energized. Lamp 55 is in the same circuit with the solenoid to relay 29. When a break or stoppage in the distribution of the cigarette paper occurs contacts 25 or 31 close the circuit to operate the relay 29. The relay energizes the solenoid which throws out the clutch mechanism to stop the machine. At the same time relay 29 lights signal lamp 55 to warn the operator that the machine has ceased to function owing to disruption in the cigarette paper feed.

The clutch operating solenoid 30 is normally deenergized and is electrically connected in circuit with the normally open contact means 25 and 31 so that operation of either of said contact means to circuit closing position in response to breakage or disruption of the paper feed will result in energization of the clutch releasing solenoid 30. Any suitable circuit arrangement may be provided, such as the arrangement shown in Fig. 4. According to the arrangement shown in Fig. 4, the clutch releasing solenoid 30 is connected across the terminals of a relay switch 56 in the relay mechanism 29, the operating coil of which is included in the plate circuit of electron tube 57 so that said operating coil is normally energized to maintain the relay switch open. The grid of tube 57 is connected in the plate circuit of a second tube 58 in series with the aforesaid contact means 25 and 31. With this arrangement the operation of any of the contact means 25 or 31 to closed circuit position results in a negative bias being applied to tube 57, thus making the plate circuit of the last mentioned tube inoperative and allowing relay switch 56 to close.

I claim:

1. In a cigarette paper interleaving machine of the character described, a relay switch including a pair of normally separated circuit closing contacts and an operating coil adapted to be energized to close said switch, a clutch releas-

ing solenoid connected across said contacts in series with a source of electrical energy, feeler contacts arranged so as to be normally held in open circuit position by the cigarette paper under normal operating conditions and to automatically assume closed circuit position in response to interruption of the paper feed and a pair of electronic tubes connected in circuit with said feeler contacts and with the operating coil of said relay switch and a source of electrical energy, the circuit arrangement being such that the grid of one tube is connected in the plate circuit of the other tube in series with the contacts, the operating coil of the relay switch being connected in the plate circuit of the tube having its grid connected in series with said feeler contacts.

2. In a cigarette paper interleaving machine of the intermeshing star wheel type provided with means for depositing cigarette papers in the paper receiving grooves of the star wheels, a plurality of movable star wheel engaging contacts, arranged so that each contact tends to engage the teeth of a different one of the star wheels but is held out of contact with said teeth by the cigarette papers deposited in the paper receiving grooves of the star wheels, each of said contacts being adapted to move into circuit closing engagement with the teeth of the associated star wheel when an empty groove of the star wheels travels past said contact and electrically actuated means connected in circuit with said contacts and said star wheels and functioning to arrest operation of the machine in response to movement of one of said contacts into circuit closing engagement with the star wheel, said means comprising a relay switch including a pair of normally separated circuit closing contacts and an operating coil adapted to be energized to close said switch by movement of said contacts to closed circuit position and an electrically operated clutch including a clutch releasing solenoid connected across said contacts in series with a source of electrical energy and a pair of electronic tubes connected in circuit with the star wheel engaging contacts, the operating coil of said relay switch and a source of electrical energy, the circuit arrangement being such that the grid of one tube is connected in the plate circuit of the other tube in series with the star wheel engaging contacts, the operating coil of the relay switch being connected in the plate circuit of the tube having its grid connected in series with said star wheel engaging contacts.

WILLIAM C. R. JONES.
